UNITED STATES PATENT OFFICE

THOMAS J. GOODRUM, OF HOUSTON, TEXAS

TOY

Application filed April 6, 1929. Serial No. 353,004.

This invention relates to new and useful improvements in a toy.

One object of the invention is to provide a wind-operated mechanical toy for out door or indoor use which is of attractive design and appearance and which will operate continuously in the presence of an air current.

With the above and other objects in view this invention has particular relation to certain novel features of construction, operation and arrangement of parts an example of which is given in this specification and illustrated in the accompanying drawings wherein:

15 Figure 1 shows a side view of the device.

Figure 2 shows a front elevation partly broken away, and

Figure 3 shows a plan view partly broken away.

20 Referring now more particularly to the drawings, wherein like numerals of reference designate similar parts in each of the figures the numerals 1 designate the legs of the framework which are secured in fixed relation by the cross braces 2 and which support the circular platform 3 on their upper ends.

25 Mounted in suitable bearings 4, 4 on this platform there is a transverse shaft. 30 Loosely mounted on this shaft there are the wind wheels 6, 6, which are spaced apart and whose vanes 7 are oppositely pitched, or inclined. These wheels 5, will accordingly rotate by the wind in opposite directions.

35 The hubs of these wheels have the inwardly extending fingers 8, 8, and splined on the shaft and between said wheels there is a drum 9. This drum is shiftable along said shaft and its ends have the radial fingers 10.

40 When the drum is shifted in one direction its fingers will interlock with the fingers of one of the wheels 6 and said drum will be thereby clutched with and will rotate with said last mentioned wheel and when the drum is

45 shifted in the other direction its fingers will be interlocked with the fingers of the other wheel 6 and it will be thereby clutched with and will rotate with said last mentioned wheel. The drum 9 is formed with a spool 11

50 and around which the cable 12 is wound.

This cable runs over the sheaves 13, 13 which are mounted on the brackets 14, 14 upstanding from opposite sides of the table 3, and the respective ends of the cable 12 support the elevating buckets 15, 15. These buckets 55 have the upper and lower ears 16, 16 on each side which run on the vertical tracks 17, 17 which are supported from the laterally extending arms 18, carried by the platform 3 and whose lower ends are attached to the transverse anchor bar 19.

Upstanding from the platform 3 there is a standard 20, pivoted to the upper end of which there is a shift lever 21. The upper end of this lever is bifurcated forming the fingers 22, 22 which are inwardly turned and ride in the annular groove 23 of the drum 9. The lower end of the lever 21 has an elongated bearing 24. There is a transverse rod 25 rotatable in suitable bearings 26 on the platform 3 and one end of this rod is upturned and its free end has an overturned stud 27 which works in said bearing 24. The other end of the rod 25 has an upturned arm 28 whose free end is formed with an overturned stud 29 which works in an oblong transverse slot 30 in the lower end of the lever 31. This lever is pivoted, at an intermediate point, on the standard 32, which upstands from the platform 3, and the upper end of the lever 31 carries a weight 33.

Pivottally mounted on opposite sides of the platform 3 are the bell cranks having the upstanding arms 34, 34' and also having the laterally extending arms 35, 35' respectively. The free ends of the arms 34, 34' are connected to the upper end of the lever 31 by means of the cords 36, 36'. Pivoted on opposite legs 1 are the bellcranks having the arms 37, 37' and 38, 38' respectively. The free ends of the arms 35, 37 are connected by the cord 39, and the free ends of the arms 35, 35' are connected by the cord 40. Slidably mounted in vertically aligned bearings 41, 41, carried by opposite legs 1 are the vertically movable rods 42, 42 whose upper ends are outwardly turned forming the arms 43, 43 whose free ends are formed into bearings which ride on one of the tracks 17 on each side and are disposed above the corresponding ears 16 106

of the respective buckets 15. The lower end of one of the rods 42 is connected to the free end of the arm 38' through the cord 44 and the lower end of the other rod 42 is connected to the free end of one of the arms of the bell crank 45, through the cord 46. This bell crank 45 is pivotally mounted on the standard 47 and the free end of its other arm is connected to the free end of the arm 38' 10 through the cord 48. Through the mechanism described when bucket 15 ascends it will strike the corresponding arm 43 and elevate it and the rod 42 to which it is attached thus exerting a pull through the cord 44, the arms 15 38, 37, the cord 39, the arms 35, 34 and the cord 36 to pull the weighted lever 31 over into the position shown in Figure 2 and this lever 31 will operate, through the mechanism described to shift the drum 9 into clutching 20 relation with one of the wind wheels 6, as also shown in Figure 2. When the other bucket 15 ascends it will engage and elevate the other arm 43 and rod 42 exerting a pull through the cord 46, the bell crank 45, the 25 cord 48, the arms 38', 37', the cord 40, the arms 35', 34', and the cord 36', thus swinging the weighted arm 31 over to its other position, and operating, through the mechanism connected therewith, to shift the drum 9 into 30 clutching relation with the other wind wheel 6.

The wind wheels 6 thus operate to rotate the spool 11 alternately in opposite directions and this spool operates, through the cable 12, 35 to alternately lift one bucket 15 and lower the other. The inner sides of these buckets are open and said open sides ride against the respective, vertically disposed, retainer plates 49, 49, arranged between the respective tracks 40 17. Each bucket has a bottom 50 which declines toward the adjacent plate 49 and holds the ball 51 therein, against said plate. As the bucket rises it carries the ball 51, therein, up with it until said ball reaches the opening 45 52, in said plate, whereupon the ball passes through said opening and into the chute 53 leading downwardly therefrom.

These chutes are formed of open work, preferably coiled wire, so that the balls passing through them will be visible. When said bucket reaches position to discharge said ball into its chute the corresponding rod 42 will be elevated thereby which will result in the shifting of the drum 9, as hereinabove explained, to effect the reversal of the rotation of the spool 11 and said elevated bucket will thereupon descend.

The chutes 53 follow a sinuous course downwardly and their lower ends terminate above 60 the corresponding buckets, when in the lower positions. The lower end of each chute is normally closed by a pivotally mounted gate 54 which is normally held in closed position by the corresponding weight 55. The ball 65 51 traveling down through a chute is engaged

and held, by the corresponding gate, against premature discharge from its chute. Each gate has an outwardly extended arm 56 which is positioned to be engaged by the corresponding bucket 15, when said bucket has passed 70 the lower end of the corresponding chute, and the corresponding gate is thereby opened and the ball, held by said gate, will thereupon fall out and into said bucket.

The drawings and description illustrate a preferred form of the invention, by way of illustration only, while the broad scope of the invention will be defined by the appended claims.

What I claim is:

1. A wind operated toy including a framework, a pair of wind wheels thereon having oppositely pitched vanes through which the wheels may be turned, by the wind, simultaneously, in opposite directions, a rotatable drum shiftable into clutching relation with said wind wheels alternately, a flexible member operable around the drum and reciprocable back and forth thereby, a carrier attached to each end of said member, said carriers being alternately elevated and lowered by said flexible member, means through which each carrier operates to shift said drum from clutching relation with one wind wheel into clutching relation with the other wind wheel, a pair of chutes associated with the framework, each chute having an inlet end elevated above the other, or discharge end, a body movable by gravity through each chute, each carrier being movable into one position to receive said body from the discharge end of the corresponding chute and to elevate said body and deliver it into the inlet end of said chute. 95

100

2. A wind operated toy including a framework, a pair of wind wheels thereon having oppositely pitched vanes through which the wheels may be turned, by the wind, simultaneously, in opposite directions, a rotatable drum shiftable into clutching relation with said wind wheels alternately, a flexible member operable around the drum and reciprocable back and forth thereby, a carrier attached to each end of said member, said carriers being alternately elevated and lowered by said flexible member, means through which each carrier operates to shift said drum from clutching relation with one wind wheel into clutching relation with the other wind wheel, a pair of chutes associated with the framework, each chute having an inlet end elevated above the other, or discharge, end, a body movable by gravity through each chute, each carrier being movable into one position to receive said body from the discharge end of the corresponding chute and to elevate said body and deliver it into the inlet end of said chute, a gate normally closing the discharge end of each chute, and means operable by the corresponding car- 115 120 125 130

rier, as it moves to its lower position, and effective to open the corresponding gate, to permit the discharge of said body, from said chute, into said last named bucket.

5 3. A wind operated toy including a framework, a pair of wind wheels thereon having oppositely pitched vanes through which the wheels may be turned, by the wind, simultaneously, in opposite directions, a rotatable drum shiftable into clutching relation with said wind wheels alternately, a flexible member operable around the drum and reciprocable back and forth thereby, a carrier attached to each end of said member, said carriers being alternately elevated and lowered by said flexible member, means through which each carrier operates to shift said drum from clutching relation with one wind wheel into clutching relation with the other 10 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490

In testimony whereof I have signed my name to this specification.

THOMAS J. GOODRUM.
